UNITED STATES PATENT OFFICE.

CARL J. E. WAXBOM, OF COLUMBUS, OHIO, ASSIGNOR TO THE JEFFREY MANUFACTURING COMPANY, A CORPORATION OF OHIO

MINING-MACHINE TRUCK.

1,136,301.

Specification of Letters Patent. Patented Apr. 20, 1915.

Application filed July 13, 1911. Serial No. 628,410.

To all whom it may concern:

Be it known that I, CARL J. E. WAXBOM, a citizen of the United States, residing at Columbus, in the county of Franklin and State 5 of Ohio, have invented certain new and useful Improvements in Mining-Machine Trucks, of which the following is a specification, reference being had therein to the accompanying drawing.

10 This invention relates more particularly to trucks for air driven mining machines.

In transporting mining machines from one point to another in a mine, as, for example, from one room to another, in case the mine 15 is operated upon the room and pillar plan, it is customary to provide a truck upon which the mining machine is loaded, this truck being adapted to run upon the regular mine car tracks. In mines in which the ma-

20 chines are driven by electric power it has been found possible to make these trucks self-propelling, the trucks ordinarily being provided with gearing to which the motor of the mining machine can be connected 25 when said machine is loaded upon the truck.

In the case of air driven mining machines, however, it has not been found feasible heretofore to use self-propelling trucks because of the difficulty of supplying air to the 30 machine when it is being moved from place to place in the mine. In case of the electric machines, it is entirely practical by means of trolley wires and cables to conduct current to the machine while it is being moved 35 from one room to the other; but in the case of the air driven machines it is not practically possible to employ hose or other flexible pipes to supply air to the machine while it is being moved from place to place.

40 The prime object of the present invention is to provide a self-propelling air driven mining machine truck adapted for use in mines in which air is used as the motive power.

45 A further object is to provide a power propelled truck of this character with power devices for leading a mining machine upon it.

The invention consists in the construction, 50 arrangement and combination of parts hereinafter set forth and claimed:

In the accompanying drawings, Figure 1 is a side elevation of my improved truck; and Fig. 2 is a plan view of the same, some

of the parts being broken away for the purpose of more clearly showing other parts.

The truck as shown comprises a frame structure having angle side bars 1, and 2, which are connected at their front end by transverse bars 3 and 4 and at their rear end by the transverse bar 5.

6 and 7 are cross plates rigidly secured to the side bars 1 and 2. These plates serve to strengthen the frame but are designed primarily to carry mechanism which will 65 presently be described. The front bars 3 and 4 carry a forward and downward inclined extension 8 which is designed to facilitate the loading and unloading of the mining machine. The frame is supported by 70 track wheels 9, 9 and 10, 10, which are mounted upon axles 11 and 12, said axles being rotatably mounted in bearings 13, 13 and 14, 14, respectively, on the frame.

15 is an air driven engine arranged beneath and secured to the plate 6 of the frame. The engine can be of any desired form, but, as shown, it comprises two double acting cylinders and has a crank shaft 15^a to which is secured a pinion 16. This pinion meshes 75 with and drives a spur gear 17 fast on the shaft 18 which is arranged longitudinally of the truck and is mounted in suitable bearings 19, 20 and 21 secured to the under sides of the frame plates 6 and 7. At its rear end 80 the shaft 18 carries a bevel gear 22, which meshes with bevel gears 23 and 24 loosely mounted on a transverse shaft 25. The gears 23 and 24 are provided with clutch teeth 23^a and 24^a, respectively, and a clutch 26 is 85 slidably mounted on the shaft 25 between the gears 23 and 24, said clutch being keyed on the shaft so that the clutch and shaft must turn together. The clutch 26 can be

in an inoperative position, as shown in Fig. 90 2, or can be thrown into operative engagement with either the gear 23 or the gear 24 by means of a hand lever 27. It is obvious that when the clutch engages the gear 23 the shaft 25 will be driven in one direction 100 and when the clutch engages the gear 24 said shaft will be driven in the opposite direction.

The shaft 25 at one end carries a sprocket wheel 28 which is aligned with a sprocket 105 wheel 29 on the axle 12, and the two wheels are connected by a sprocket chain 30. On the opposite side of the truck the axles 11

and 12 are provided with sprocket wheels 31 and 32 which are connected by a sprocket chain 33. With the connections described it is clear that the truck axles and wheels can be driven in either direction from the engine 15.

A spur gear 34 is loosely mounted on the shaft 18 at a point adjacent the bearing 21. This gear carries clutch teeth 34^a, and 35 is a sliding clutch keyed to the shaft 18 and adapted to coöperate with the clutch teeth 34^a. 36 is a hand lever by means of which the clutch 35 can be thrown into and out of engagement with the gear 34. A gear 37 is arranged to mesh with the gear 34, the former gear being mounted on a stub shaft 38 which is rotatably mounted in a bearing 39 carried by the frame plate 7.

40 is a reciprocating piston air compressor secured to the lower part of the truck frame and arranged to be driven by suitable crank and pitman connections from the gear 37.

The compressor 40 has a discharge pipe 41 which connects with a pipe 42 leading to an air tank 43. The pipe 42 extends forward and connects with a pipe 45 from which air is supplied to the engine 15. The pipe 45 is provided with a stop or throttle valve 46 and the pipe 42 is provided with a similar valve 47 at a point adjacent the supply pipe 45. The pipe 42 also has a pressure reducing valve 48 which is arranged so that the discharge pipe 41 of the compressor leads into the pipe 42 between the tank 43 and the said pressure reducing valve 48.

It will now be seen that by closing the valve 47 and opening the valve 46 air supplied to the pipe 45 can be conducted to the engine 15 and the latter caused to drive the compressor 40 so as to charge the tank 43 with compressed air, and this can be done while the truck is at rest. Then when it is desired to move the truck the valve 46 can be closed and the valve 47 opened so as to draw air from the tank 43, the reducing valve 48 serving to reduce the pressure of the air to a suitable amount for driving the engine 15, and thus the truck can be propelled from place to place by means of the compressed air stored in the tank 43.

To facilitate the loading of a mining machine upon the truck the latter is provided with a winding shaft or drum 49 which is mounted in suitable bearings at the rear end 55 of the truck.

50 is a chain connected at one end to the drum 49 and adapted to be wound upon it. For the actuation of the winding drum I provide both hand and power devices, either 60 of which can be used as may be desired. The hand device comprises a ratchet wheel 51 secured to the drum, a hand lever 52 arranged to swing around the axis of the drum and carrying a driving pawl 53 to coöperate 65 with the ratchet wheel 51.

54 is a stationary pawl or detent arranged to prevent backward movement of the winding drum.

In order to drive the winding drum 49 by power I provide on one end of the drum 70 a sprocket wheel 55 and in front of the drum is a stub shaft 56 which carries a sprocket wheel 57 in line with the whel 55, the two sprocket wheels being connected by a chain 58. The stub shaft 56 is rotatably mounted 75 in a suitable bearing 59 on the truck frame and carries at its inner end a bevel gear 60. This gear meshes with a bevel gear 61 which is loosely mounted on the shaft 18. The gear 61 carries clutch teeth 61^a and a slide- 80 able clutch 62 is keyed upon the shaft 18 in position to coöperate with the clutch teeth 61^a. By means of a hand lever 63 the clutch 62 can be thrown into and out of engage- 85 ment with the clutch teeth of the gear 61. When the gear 61 is clutched to the shaft 18 it is clear that said shaft, if driven by the engine 15, will in turn drive the stub shaft 56, and it, through the sprocket wheel and chain connections, will drive the finding 90 drum 49. It will be understood that in load- 95 ing the mining machine upon a truck the chain 50 is connected to the machine and then by turning the winding drum, either by hand, or by power, the chain is wound up and the machine is drawn upon the truck.

The manner in which my improved truck is operated and used in the mine will now be readily understood. In moving the mining machine into the room where it is to be 100 used the truck is driven by means of air previously stored in the tank 43. When the machine has been unloaded from the truck adjacent the face which is to be undercut, the air supply pipe 45 of the truck can be 105 connected with the same pipe or hose which supplies the air for driving the mining machine, it being understood that the air supply pipes are carried through the entries of the mine and into the various rooms. The 110 valve 47 having been closed and the valve 46 opened the engine 15 is now driven by the air entering through the supply pipe 45 and, with the gears 23, 24 and 61 running idle, the clutch 35 is thrown to connect the gear 115 34 to the shaft 18 so as to drive the compressor 40. The latter discharges into the storage tank 43 and thus, while the coal is being undercut, a supply of compressed air is being stored in the tank 43. The mechanism can be designed to compress the air in the tank 43 to any desired amount, the degree of compression being determined by the relative dimensions of the engine 15, the compressor 40 and the driving connections 125 between them. A suitable degree of compression would be about twenty times the pressure in the supply pipes of the mine.

When the undercutting of the coal has been finished the mining machine can be 130

drawn to and loaded upon the truck by means of the winding drum and chain, the drum being actuated either by hand or by power as may be desired. If it is to be driven by power, it is only necessary to throw in the clutch 62 and start the engine 15, if it is not running. The air to drive the engine for this purpose will preferably be taken from the mine supply pipe. When the machine has thus been loaded upon the truck, the valve 46 is closed and the pipe 45 is disconnected from the air supply pipe. The clutches 62 and 35 having been thrown out the valve 47 is opened and air is drawn from the tank 43 to drive the engine 15, the pressure of said air being suitably reduced in passing through the reduction valve 48. The clutch 26 is then thrown into engagement with one or the other of the gears 23 and 24, according to the direction in which the truck is to be driven, and the truck is thus propelled under its own power to move the machine to another room, or some other place in the mine where it is to be used. There the same procedure is repeated, that is, the tank 43 is resupplied with air while the truck is standing during the undercutting of the coal. Of course the tank 43 of the truck can be stored with compressed air at any point in the mine entries where connection can be made with the air supply pipes of the mine.

What I claim is:

1. In a truck for transporting mining machines and the like, the combination of a wheel-supported frame, a tank on the frame for storing elastic fluid under pressure, an elastic fluid engine mounted on the frame, driving connections between the engine and the truck wheels, said engine having an inlet conduit adapted to be connected independently of the said tank to a source of fluid supply external to the truck, and a manually controllable connection between the tank and the engine, whereby the engine can be driven by fluid drawn from the tank, substantially as set forth.

2. In a truck for transporting mining machines and the like, the combination of a wheel-supported frame, an elastic fluid engine mounted on the frame, a winding drum on the frame for loading a mining machine or the like upon the truck, driving connections between the engine and the truck wheels, driving connections between the engine and the winding drum, the said engine having an inlet pipe adapted to be connected to a source of fluid supply independent of the truck, a tank on the truck for storing fluid under pressure, and connections between the tank and the engine inlet, whereby the engine can be driven by fluid drawn from the tank, substantially as set forth.

3. In a truck for transporting mining machines and the like, the combination of a

wheel-supported frame, an elastic fluid engine mounted on the frame, driving connections between the engine and the truck wheels, a tank on the truck for storing air under pressure, an air compressor for forcing air into said tank, driving connections between the engine and the said compressor, a supply pipe for the engine adapted to be connected to a source of fluid supply independent of the truck, and means for conducting air from the tank to said engine, whereby the engine can be driven by fluid drawn from the tank, substantially as set forth.

4. In a truck for transporting mining machines and the like, the combination of a wheel-supported frame, an elastic fluid engine mounted on the frame, driving connections between the engine and the truck wheels, a tank on the truck for storing air under pressure, an air compressor for forcing air into the tank, driving connections between the engine and the said compressor, a supply pipe for the engine adapted to be connected to a source of fluid supply independent of the truck, and means comprising a conduit and a pressure reducing device for conducting air from the tank to the inlet of the engine, whereby the engine can be driven by fluid drawn from the tank, substantially as set forth.

5. In a truck for transporting mining machines and the like, the combination of a wheel-supported frame, an elastic fluid engine mounted on the frame, a winding drum mounted on the frame, driving connections between the engine and the winding drum, said engine having an inlet pipe adapted to be connected to the source of fluid supply independent of the truck, a tank carried by the truck, an air compressor forcing air into said tank, driving connections between the air compressor and the engine, and means for conducting air from the tank to the inlet of the engine, whereby the engine can be driven by air drawn from the tank, substantially as set forth.

6. In a truck for transporting mining machines and the like, the combination of a wheel supported frame having a smooth bed along which a mining machine may be slid, an elastic fluid engine mounted upon the frame below the said smooth bed, driving connections between the engine and the truck wheels, a tank on the truck for storing fluid under pressure, connections between the tank and the engine whereby the engine can be driven by fluid drawn from the tank, a winding drum at one end of the frame, means for rotating the drum, and a flexible device connected with the drum to be wound thereon and adapted to be connected at its other end to a mining machine.

to haul the said machine along the said smooth bed.

7. In a truck for transporting mining machines and the like, the combination of 5 a wheel supported frame having a smooth bed along which a mining machine may be slid, an elastic fluid engine mounted upon the frame, driving connections between the engine and the truck wheels, a tank on the 10 truck for storing fluid under pressure, connections between the tank and the engine whereby the engine can be driven by fluid drawn from the tank, a winding drum at one end of the frame, a driving connection 15 between the engine and the drum whereby the drum can be rotated, and a flexible device connected with the drum to be wound thereon and adapted to be connected at its other end to a mining machine to haul the 20 said machine along the said smooth bed.

8. In a truck for transporting mining machines and the like, the combination of a 25 wheel supported frame having a smooth bed along which a mining machine may be slid, a motor permanently mounted upon the frame in such a position that the said smooth bed is left unobstructed, driving connections between the motor and the truck

wheels, a winding drum at one end of the frame, means for rotating the drum, and a 30 flexible device connected with the drum to be wound thereon and adapted to be connected at its other end to a mining machine to haul the said smooth bed.

9. In a truck for transporting mining machines and the like, the combination of a 35 wheel supported frame having a smooth bed along which a mining machine may be slid, a motor mounted upon the frame, driving connections between the motor and the truck wheels, a winding drum at one end of the frame, a driving connection between the motor and the drum whereby the drum can be rotated, and a flexible device connected 40 with the drum to be wound thereon and adapted to be connected at its other end to a mining machine to haul the said machine along the same smooth bed.

In testimony whereof I affix my signature, 45 in presence of two witnesses.

CARL J. E. WAXBOM.
